DOOR LOCKS

Herbert G. Shaw, West Haven, Conn., assignor to Sargent & Company, New Haven, Conn., a corporation of Connecticut

Application March 10, 1955, Serial No. 493,379

5 Claims. (Cl. 292—36)

This invention relates to door locks and more particularly to a lock adapted for mounting upon a communicating door such as a door between a bedroom and bathroom, for example, wherein a pair of dead bolts are mounted, one of which is operated from one side of the door and the other from the other side.

In some instances such, for example, as where a suite of rooms comprises two rooms having a bathroom situated between them with communicating doors to both of the adjoining rooms, it is desirable to employ a lock upon the doors leading into the bathroom which is provided with two dead bolts, one of which may be actuated from the bedroom-side of the door and the other from the bathroom-side of the door. Also in certain instances it is desirable that the locks be so constructed that both dead bolts may not be protracted at the same time or, in other words, so that when the dead bolt mechanism on one side of the door is operated, the other mechanism will be prevented from operation. This is effected in the present instance by mounting in the lock case a movable member, in this instance a pivoted member, such that this member will be actuated when either of the dead bolts is thrown or projected, the member being moved into engagement with a portion of the other dead bolt mechanism to block it against movement. As illustrated, this interlocking means between the dead bolts is in the form of a lever pivoted at its intermediate portion in the manner of a walking beam having arms extending toward the rollbacks which operate the dead bolt so that when one rollback is rotated, it will engage the adjacent arm of the walking beam and throw the other arm into engagement with the other rollback in such a manner as to prevent movement of the latter. Therefore, if one bolt has been thrown or protracted, the other will be restrained from being operated and will be restrained in its retracted position.

One object of the present invention is to provide a new and improved lock mechanism having a pair of dead bolts and mechanism connecting said bolts whereby either thereof may not be protracted when the other is in protracted position.

A still further object of the invention is the provision of a lock mechanism of the character described having a pair of dead bolts, one being operated from one side of the door and the other from the other side of the door through rollbacks mounted in the lock case, and to provide a member movably mounted in the lock case which will be moved by the operation of one of the rollbacks to position to prevent the operation of the other rollback.

Still another object of the invention is to provide a lock mechanism having a pair of dead bolts and independent actuating mechanism for each of said bolts, one of which is operated from one side of the door and the other from the opposite side of the door, and to provide a member movably mounted in the lock case which is effective to prevent the operation of one of said actuating mechanisms when the other has been operated to protract the associated bolt.

2

To these and other ends the invention consists in the novel features and combinations of parts to be herein-after described and claimed.

In the accompanying drawings:

5 Fig. 1 is a front elevational view of a lock mechanism embodying my improvements;

Fig. 2 is a sectional view on line 2—2 of Fig. 1;

Fig. 3 is a sectional view on line 3—3 of Fig. 2;

10 Fig. 4 is a view similar to Fig. 3 showing one of the bolts in protracted position;

Fig. 5 is a perspective view of the dogging member pivotally mounted in the lock case to prevent the protraction of one of the dead bolts when the other has been protracted.

15 To illustrate a preferred embodiment of my invention, I have shown a door lock mounted upon a door 10, the lock mechanism being adapted to cooperate with a strike plate 11 mounted upon the door jamb 12. As shown in Figs. 3 and 4, the strike plate is provided with an elongated opening 13 which, as will be hereinafter described, is adapted to receive the latch bolt as well as the two dead bolts.

20 The lock mechanism comprises a casing 14 within which is reciprocably mounted a latch bolt 15 to which is secured the usual stem 16, the bolt being urged to protracted position by the spring 17 which bears against a member 18 secured to the case.

25 At the rear end of the stem 16 is secured the usual yoke 19 which is operated by a double-armed rollback 20, the rollback being in turn operated by the knobs 21 and 22 at either side of the door. The latch bolt structure may be of usual form and no further description thereof is required.

30 35 As previously stated, two dead bolts 23 and 24 are provided in the lock case, these dead bolts being adapted to be reciprocated through openings 25 and 26 in the face plate 27 of the lock case, as shown more particularly in Figs. 3 and 4. The mechanism for actuating the dead bolts is identical except that one is designed to be operated from one side of the door and the other from the other side of the door. As with this exception the mechanism is the same, the description of one will suffice for both.

40 45 Pivoted to the rear portion of each of the dead bolts is one end of a link 28, the other end of the link being pivoted at 29 to a rollback 30. This rollback, as shown, is of irregular shape in that it is provided with a relatively straight front face 31 and an arcuate face 32 for a purpose to be hereinafter explained. Each of these rollbacks is adapted to be operated by a turn button, one being operated by the turn button 33 at one side of the door and the other by the turn button 34 at the other side of the door. Secured to each of the turn buttons is a stem 35 of polygonal cross section, this stem being nonrotatably engaged with a collar 36 rotatably mounted in the wall of the casing, and the rollbacks are secured to these collars so that when the turn buttons are rotated, the rollbacks will likewise be rotated. Suitable stops (not shown) may be provided to limit the rotation of the turn buttons.

50 55 60 Pivoted upon a wall of the lock case at 38 is a walking beam lever 39. Each end of this lever is provided with a projecting arm 40 in position to engage the adjacent rollback. It may be noted from Fig. 3 that when both dead bolts are retracted, as shown in this figure, the lever 39 is idle in that neither of the arms 40 are engaged with the adjacent rollbacks but stand in a position slightly spaced therefrom which is the normal position of the parts when the door is not locked. The latch bolt 15, of course, cooperates with the strike plate 11 in holding the door closed in the usual manner.

room turns the button 33 or 34, depending upon which room he is occupying at the time. When the button 34 is turned, the lower rollback is rotated, as shown in Fig. 4, this rollback serving through the associated link 28 to protract the dead bolt 23 to lock the door. During the rotation of the rollback, the straight side 31 thereof engages the arm 40 of the lever 39 and rocks this lever in a clockwise direction until the straight side 31 passes by the arm 40 and the latter rides upon the arcuate or cammed surface 32. This surface is formed upon an arc described about the axis of the rollback as a center so that the lever 39 is maintained in the position shown so long as the arm 40 is in contact with the surface 32. It will be noted that in this position the other arm 40 of the lever 39 is moved against the straight surface 31 of the rollback of the dead bolt 24 so as to block any movement of this rollback to protract the bolt 24. Thus the latter bolt cannot be protracted by the turn button 33 while the bolt 23 is in protracted position.

Likewise if the bolt 23 is retracted and the upper rollback rotated by the button 33, as shown in dotted lines in Fig. 3 to protract the latch bolt 24, the straight side 31 of this rollback will similarly act as a cam and, by engaging the upper arm 40 of the lever 39, will move this lever against the straight side 31 of the lower rollback and prevent actuation of the latter. Thus while each of the bolts may be operated from one side of the door, neither can be thrown while the other is in protracted position. Thus one entering the bathroom, for example, and locking the door from that side, cannot be locked in by the actuation of the other dead bolt from the other side.

It will be understood that this particular mechanism is sometimes used in connection with additional locking mechanism which will enable the door to be locked from one side even though it has been previously locked from the other side by the dead bolt mechanism shown herein, this additional mechanism not being part of the present invention.

While I have shown and described a preferred embodiment of my invention, it will be understood that it is not to be limited to all of the details shown, but is capable of modification and variation within the spirit of the invention and within the scope of the claims.

What I claim is:

1. A door lock comprising a casing, a pair of dead bolts reciprocably mounted in the casing, a rollback in the casing connected to each bolt to actuate the same, one of said rollbacks being actuated from one side of the door and the other from the other side of the door, a lever pivotally mounted between said rollbacks and having a part in the path of each of the rollbacks whereby when one rollback is actuated to protract the associated bolt, one of the parts on said lever is moved in position to prevent rotation of the other rollback.

2. A door lock comprising a casing, a pair of dead bolts reciprocably mounted in the casing, spaced rollbacks rotatably mounted in the casing, one connected to each of said bolts to actuate the same, a lever pivotally mounted in the casing between said rollbacks and having spaced arms thereon, one arm lying in the path of each of said rollbacks, and each of said rollbacks having a portion to engage one of said arms and move said lever into position to dog the other rollback, and a part to maintain said lever in said position during continued movement of the rollback.

3. A door lock comprising a casing, a pair of dead bolts reciprocably mounted in the casing, a pair of rollbacks in the casing, one connected to each bolt to actuate the same, said rollbacks being in spaced relation, a lever pivotally mounted in the casing between said rollbacks and having spaced arms, one arm lying in the path of each of the rollbacks, and each of said rollbacks having a cam surface to engage the associated arm and move said lever about its pivot to a position whereby the other arm blocks the other rollback and also having an arcuate surface to engage the arm of the lever and retain the latter in position to which it is moved.

4. A door lock comprising a casing, a pair of dead bolts reciprocably mounted therein, actuating means in the casing for each bolt to protract one bolt independently of the other, a member movably mounted in the casing in the path of, and adapted to be engaged by, a part of the actuating means of one bolt when it is protracted and moved by said actuating means to a position to engage and block the actuating means of the other bolt to prevent protraction of the latter.

5. A door lock comprising a casing, a pair of dead bolts reciprocably mounted in the casing, a rollback in the casing connected to each bolt to actuate the same, one of said rollbacks being actuated from one side of the door and the other from the other side of the door, a member movably mounted in the casing and having a part in the path of each of said rollbacks whereby one rollback is actuated to protract its associated bolt, one of the parts on said member is moved to a position to prevent rotation of the other rollback in a direction to protract its associated bolt.
